UNITED STATES PATENT OFFICE

CARL CLIFTON KOFORD, OF ERIE, PENNSYLVANIA, ASSIGNOR TO THE NUBONE COMPANY, INC., OF ERIE, PENNSYLVANIA, A CORPORATION OF PENNSYLVANIA

CORSET

Application filed April 12, 1928. Serial No. 269,571.

This invention relates to improvements in corsets and particularly corsets including brassière fronts. The corset is of a type extending from the waist below the hip line and one of the features of the invention is to provide elasticity at the lower front sides of the corset. Another feature of the invention is to provide a detachable brassière front formed with a waist forming belt stocking 5 supporter and bust portions extending therefrom. Other features and details will appear from the specification and claims.

A preferred embodiment of the invention is illustrated in the accompanying drawings 15 as follows:—

Fig. 1 shows a front quarter view of the corset.

Fig. 2 a similar view with the brassière detached at one side.

Fig. 3 a rear view of the corset.

Fig. 4 a front view of the corset with the brassière detached.

Fig. 5 a like view of the corset with the brassière attached at one side.

A marks the back portion of the corset, and A' the front portion of the corset. These are preferably connected by lacings α at the sides. The front portion is provided with a line of separable fasteners α' extending centrally and upwardly through the portion and these are used normally for removing and closing the corset. A brassière front B is provided with a belt B' extending across the waist line below the busts. This belt is made double and has depending tabs C' and C'', one for each part of the belt. The ends of this belt are provided with elastic inserts or portions C and also provided with a line of detachable fasteners b' which are adapted to engage complementary members b at the sides of the corset. The belt has an upwardly extending portion b^2 at the center and individual bust covering pockets b^3 of relatively soft material, such as silk, are secured to the central portion b^2 and the laterally extending portions of the belt. The separable fasteners b' are extended along this bust pocket so that it may be detachably secured to complementary members b on the 50 corset.

Elastic stocking supporters D D are secured in the usual manner to the tabs C' and C''. The front has portions d cut out of the material at the bottom of the front and at each side thereof. These cut-out portions d are 55 covered with elastic material D'. It will be noted that these cut-out portions are below the hip line and in line with the legs of the wearer so as to yield and add to the comfort of the wearer with extreme flexures of the 60 legs.

It will be noted that the front with the lacings at the sides permits of the interchange of different fronts to initially adjust the corset as to size to the wearer. Ordinarily 65 these lacings are left in place permanently, the opening and closing of the corset being accomplished by the fasteners.

It will also be observed that the brassière front due to the elastic pull at the ends of 70 the belt portion is made to adjust itself closely to the waist line of the wearer; that the depending stocking supporters tend to hold it in its proper downward position; that the line connection at the edges with the corset 75 tends to position this belt at the waist line and give it proper support; and that the individual bust pockets extending upwardly from this belt, the belt being so complete in itself without these, may be made of relatively soft material. The connection of the edges of the belt with the corset back in connection with the stocking supporter tends to position the back of the corset on the wearer and these supporters in addition to this also 80 tend to flatten the diaphragm portion, or double portion of the belt. It will also be noted that the belt overlaps the front of the corset. Consequently it is possible to supply 85 different types of belt, both as to size and material with the same corset. This simplifies the original fitting and reduces the number of sizes of corset necessary to carry and also makes it possible to change the belt material for different types of wear. This is 90 particularly true as to the bust covering b^3 , thus giving a greater range of use for the same corset.

What I claim as new is:—

1. In a corset, corset front and back por- 100

- tions extending from the waist downwardly; and a brassière front having a line of detachable fasteners at each end detachably securing the brassière front to the corset at the ends, the brassière front comprising a belt adapted to extend across the waist below the bust and overlapping the corset front and individual bust pockets extending from the belt upwardly.
10. 2. In a corset, corset front and back portions extending from the waist downwardly; and a brassière front having a line of detachable fasteners at each end detachably securing the brassière front to the corset at the ends, the brassière front comprising a belt adapted to extend across the waist below the bust and overlapping the corset front and having an upward extension adapted to extend between the busts of a wearer, and individual bust pockets secured to the belt and extension.
15. 3. In a corset, corset front and back portions extending from the waist downwardly; and a brassière front having a line of detachable fasteners at each end detachably securing the brassière front to the corset at the ends, the brassière front comprising a belt adapted to extend across the waist below the bust and overlapping the corset front and having an upward extension adapted to extend between the busts of a wearer, and individual bust pockets secured to the belt and extension.
20. 4. In a corset, corset front and back portions extending from the waist downwardly; and a brassière front having a line of detachable fasteners at each end detachably securing the brassière front to the corset at the ends, the brassière front comprising a belt adapted to extend across the waist below the bust and overlapping the corset front and individual bust pockets extending from the belt upwardly, the edges of the pockets being detachably secured to the corset at the sides.
25. 5. In a corset, corset front and back portions extending from the waist downwardly; and a brassière front having a line of detachable fasteners at each end detachably securing the brassière front to the corset at the ends, the brassière front comprising a belt adapted to extend across the waist below the bust and overlapping the corset front and having an upward extension adapted to extend between the busts of a wearer, and individual bust pockets secured to the belt and extension, the edges of the pockets being detachably secured to the corset at the sides.
30. 6. In a corset, corset front and back portions extending from the waist downwardly; and a brassière front having a line of detachable fasteners at each end detachably securing the brassière front to the corset at the ends, the brassière front comprising a belt adapted to extend across the waist below the bust and overlapping the corset front, individual bust pockets extending from the belt upwardly, and elastic portions arranged at the ends of the belt.
35. 7. In a corset, corset front and back portions extending from the waist downwardly; and a brassière front having a line of detachable fasteners at each end detachably securing the brassière front to the corset at the ends, the brassière front comprising a belt adapted to extend across the waist below the bust and overlapping the corset front and individual bust pockets extending from the belt upwardly, and elastic portions arranged at the ends of the belt.
40. 8. In a corset, corset front and back portions extending from the waist downwardly; and a brassière front having a line of detachable fasteners at each end detachably securing the brassière front to the corset at the ends, the brassière front comprising a belt adapted to extend across the waist below the bust and overlapping the corset front and individual bust pockets extending from the belt upwardly, and elastic portions arranged at the ends of the belt.
45. 9. In a corset, corset front and back portions extending from the waist downwardly; and a brassière front having a line of detachable fasteners at each end detachably securing the brassière front to the corset at the ends, the brassière front comprising a belt adapted to extend across the waist below the bust and overlapping the corset front and individual bust pockets extending from the belt upwardly, and elastic portions arranged at the ends of the belt.

individual bust pockets extending from the belt upwardly, said belt having stocking supporters extending downwardly from the belt.

7. In a corset, corset front and back portions extending from the waist downwardly; and a brassière front having a line of detachable fasteners at each end detachably securing the brassière front to the corset at the ends, the brassière front comprising a belt adapted to extend across the waist below the bust and overlapping the corset front and individual bust pockets extending from the belt upwardly, said belt being double, the plies being free to move on each other and having stocking supporters extending from each part of the double belt.

8. A brassière front having a belt portion adapted to extend across the waist of a wearer and terminating at the sides of the wearer and adapted to be attached to the sides of a corset below the busts having elastic portions at each end, said belt portions being double, the plies being free to move on each other and having stocking supporters extending from each part of the double belt and individual bust pockets of lighter material extending upwardly from the belt portions.

9. A brassière front having a belt portion adapted to extend across the waist of a wearer and terminating at the sides of the wearer and adapted to be attached to the sides of a corset below the busts having elastic portions at each end, said belt portions being double, the plies being free to move on each other and having stocking supporters extending from each part of the double belt, said belt portions having an upwardly extending portion adapted to extend between the busts of a wearer; and individual bust pockets of lighter material secured to the extension and to the belt portions.

In testimony whereof I affix my signature.

CARL CLIFTON KOFORD.
